DOROTHY LONG, OF NEW YORK, N. Y., ASSIGNOR TO FRANKLIN SIMON & COMPANY, INC., OF NEW YORK, N. Y., A CORPORATION OF NEW YORK

DESIGN FOR A DRESS

Application filed September 20, 1929. Serial No. 32,813. Term of patent 3½ years.

To all whom it may concern:

Be it known that I, DOROTHY LONG, a citizen of the United States, and a resident of the city of New York, borough of Manhattan, in the county of New York and State of New York, have invented the new, original, and ornamental Design for Dress, of which the following is a specification.

Reference is had to the accompanying drawing, forming part thereof, wherein the dominant feature of the dress consists of a triangular panel extending from the neck opening downwardly at a slight angle forming part of the blouse and merging at one side into a collar draped around the neck

and over the shoulders with one corner of the triangle meeting the drapery below one shoulder.

Figure 1 is a front perspective view of a dress showing my new design, the same being illustrated on a figure indicated by dotted lines;

Figure 2 is a rear perspective view of the dress shown in Figure 1, the same being illustrated on a figure indicated by dotted lines.

I claim:

The ornamental design for a dress substantially as shown and described.

DOROTHY LONG.
